TERMINAL TO BASE CONNECTION

Edmund Stanwyck, Newburgh, N.Y.

Application August 28, 1956, Serial No. 606,590

3 Claims. (Cl. 339—220)

This invention relates in general to new and useful improvements in electronic parts, and more specifically to an improved terminal device connection which facilitates the attachment of electronic components.

In the manufacture of electronic components, particularly coils, relatively small terminals are attached to a base for the purpose of both securing the coil to the chassis of the electronic instrument and for forming a connection between the electrical components of the electronic part and the wiring circuit of the electronic instrument. However, these terminals are relatively small and in many instances it is necessary to connect wires of relatively great size thereto. This is particularly true in the instance of resistors and the like. In order to hold the wires in place, it is normally necessary to twist them about the terminal. Because of the relatively large diameter of the wires and the stiffness thereof, this is a difficult operation and is not only time consuming, but oftentimes results in the damaging of the terminal. Also, in certain instances it is necessary to attach both fine wires and relatively thick wires to the same terminal. The fine wire in many instances must be attached first and the thick wire afterwards. In the attachment of thick wire the fine wire is oftentimes broken.

It is therefore the primary object of this invention to provide an improved terminal to base connection which is of such a nature whereby there is automatically formed a wire socket for receiving and holding in frictional contact with the terminal a relatively large cross-sectional wire.

Another object of this invention is to provide an improved terminal to base connection which includes a terminal having prongs struck therefrom, the prongs being passed into the base to secure the terminal in place, the formation of the prongs resulting in openings in the terminal, the openings being exposed in overlapping relation to the ends of the base whereby there is provided sufficient space for the passage of the wire to be connected to the terminal.

Still another object of this invention is to provide an improved terminal and base construction for electronic parts, the terminal being secured to the base by means of prongs struck therefrom, the prongs leaving openings in the terminal, the terminal being provided with a wire attaching flange which is connected to the remainder of the terminal intermediate the ends of one of the openings, the portion of the opening disposed within the attaching flange forming a wire receiving socket whereby relatively large wires may be positioned therein prior to soldering to the terminal and at the same time may be attached to the attaching flange, the other wire or wires being of a relatively small size as compared to the wire received in the wire socket.

A further object of this invention is to provide an electronic part which includes a support, a base on the support and at least one terminal carried by the base, the terminal being provided at one end thereof with means

2

for attachment to an electronic instrument chassis and at the other end with an attaching flange, the terminal being attached to the base by means of prongs struck out from the terminal, the formation of the prong resulting in the formation of openings, one of the openings in the terminal being disposed at an intersection of the flange with the remainder of the terminal to form a wire receiving socket in the flange, there being mounted on the support a first electrical component formed of relatively small wire and attached to the attaching flange, there also being a second electrical component such as a relatively large wire which is received in the wire socket.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

20 Figure 1 is a side elevational view of a coil which employs the terminal to base connection which is the subject of this invention, the coil including a coil component and a resistor;

25 Figure 2 is a top view of the coil of Figure 1 and shows further the details thereof;

Figure 3 is an enlarged transverse sectional view taken substantially upon the plane indicated by the section line 3—3 of Figure 1 and shows further the relationship of the terminal with respect to the base and the wires attached to the terminal;

30 Figure 4 is an enlarged fragmentary sectional view taken substantially upon the plane indicated by the section line 4—4 of Figure 3 and shows the specific relationship of one of the terminals with respect to the base and the manner in which the wires of the electrical components are attached thereto;

Figure 5 is a fragmentary plan view similar to Figure 2 and shows the manner in which additional wires may be attached to the terminal; and

40 Figure 6 is an enlarged fragmentary longitudinal sectional view taken through the electronic part of Figure 1 and shows the details of the relationship between a terminal thereof, a base thereof and wires connected to the terminal.

45 Referring now to the drawings in detail, it will be seen that there is illustrated in Figures 1 through 4, inclusive, a preferred electronic part which is referred to in general by the reference numeral 10. The electronic part 10 is in the form of a coil and includes a tubular support 12 which has a base 14. The tubular support 12 and the base 14 are preferably formed of an insulating material and may be integrally molded or may be in separate parts with the base 14 telescoped over the support 12.

50 In order that the base 14 may be connected to a printed circuit board or the like and at the same time complete the electrical connection between the electronic part 10 and the printed circuit of the printed circuit board, there is carried by the base 14 a plurality of terminals 16.

55 Each of the terminals 16 is formed of an elongated strip of material and includes a body portion 18 which terminates at its lower end in an offset mounting portion 20 which is used to secure the terminal 16 to a printed circuit board (not shown) and form an electrical contact between the printed circuit thereof. The opposite end of the body portion 18 is in the form of an outwardly directed attaching flange 22.

60 Referring now to Figure 4 in particular, it will be seen that there is struck from the body portion 18 a pair of prongs 24 and 26. The formation of the prong 24 results in the existence of an elongated opening 28 in the lower part of the body portion 18 while the formation of the prong 26 results in the existence of an elongated

opening 30 in the upper part of the body portion 18. The terminal 16 is so secured to the base 14 whereby the opening 28 overlaps the lower end of the base 14. The opening 30 is so positioned whereby the connection between the attaching flange 22 and the base portion 18 is disposed intermediate the ends of the opening 30. Inasmuch as the opening 28 extends below the lower end of the base 14, there is produced a wire socket in the terminals 16 between the terminals 16 and the base 14. Also, the opening 30 is so located with respect to the attaching flange 22 that there is disposed in the attaching flange 22 a wire socket 32, which is best illustrated in Figure 3, the wire socket extending along the exterior surface of the base 14.

Wound upon the terminal support 12 is a coil 34. The coil 34 includes a wire 36 which is of a relatively small size. The wire 36 is wrapped around the attaching flange 22 for mechanical securement thereto prior to the soldering operation. As is best illustrated in Figure 3, each attaching flange 22 has side edges in which there are formed wire receiving notches 38 which slope away from the wire socket 32. Thus when an end of the wire 36 is wrapped about the attaching flange 22 in the notches 38, the wire 36 is urged away from the wire socket 32.

Disposed about an intermediate portion of the coil 34 is a protective strip 40. Engaging the protective strip 40 is a resistor 42 which includes connecting wires 44. The connecting wires 44 are of a relatively large cross-section as compared to the wire 36 and cannot be easily bent about the terminals 16 for attachment thereto. However, the wires 44 are of a size to be snugly received in the wire sockets 32 of several of the terminals 16. This is best illustrated in Figure 3. Inasmuch as the ends of the wires 36 are spaced from the wire sockets 32, it will be seen that there is no interference between the wires 44 and the ends of the wires 36 so that the wires 36 are not actually broken. On the other hand, a single soldering operation may result in the forming of a solder drop 46 which will retain in place both the wire 44 and an end of the wire 36, as is best illustrated in Figure 4.

Referring now to Figures 5 and 6 in particular, it will be seen that there is illustrated a slightly modified form of an electronic part which is referred to in general by the reference numeral 48. The electronic part 48 is almost identical to the electronic part 10 and includes a tubular support 50 having mounted on the lower end thereof a base 52. Connected to the base 52 is a plurality of the terminals 16. The electronic part 48 also includes a coil 34 and a resistor 42. The electronic part 48 differs from the electronic part 10 only in that the base 52 is much shorter than the base 14.

Referring now to Figure 6 in particular, it will be seen that the length of the base 52 is such that the terminal 16 extends both above and below the base 52. The opening 28 overlaps the lower end of the base 52 to form a wire socket 56 which is identical with the wire socket formed between the opening 28 and the base 14. The opening 30 also results in the formation of the same type of wire socket 32. However, the attaching flange 22 is now disposed at the upper end of the base 52 and the wire socket 32 is disposed at the upper end of the base 52.

The wire 36 of the coil 34 is wrapped about the attaching flange 22 in the same manner as described above with respect to Figures 1 through 4, inclusive. On the other hand, the wire 44 of the resistor 42 in lieu of being passed down parallel to the base 14, as is illustrated in Figure 4, is pushed through the wire socket 32 up adjacent to the attaching flange 22 so as to facilitate the positioning of a solder drop 58. Other wires 60 are passed through the wire sockets 56 and secured to the terminals 16 by a solder drop 62.

From the foregoing description of the present invention, it will be seen that the openings formed by the prongs of the terminals and serve the useful purpose of

forming mechanical connections between wires and the terminals prior to the forming of solder joints thus eliminating the necessity of bending heavy wire about the relatively weak prong.

The foregoing is considered as illustrative only of the principles of the invention. Further, since numerous modifications and changes will readily occur to those skilled in the art, it is not desired to limit the invention to the exact construction and operation shown and described, and accordingly, all suitable modifications and equivalents may be resorted to, falling within the scope of the invention as claimed.

What is claimed as new is as follows:

1. For use in electronic parts, a terminal and base construction, said terminal and base construction comprising a tubular base member having a longitudinal axis, a terminal, said terminal having at least one prong struck therefrom, said prong passing into said base member and securing said terminal to the arcuate surface of said base member parallel to said longitudinal axis, the formation of said prong presenting an opening in said terminal, said opening being spaced relative to said base member and forming in conjunction with an adjacent portion of said base surface a wire socket intermediate said terminal and said base member, said terminal including an attaching flange, said attaching flange being disposed in angular relation to the remainder of said terminal and extending away from said base member, and said flange being connected to the remainder of said terminal intermediate the ends of said opening whereby said wire socket is disposed partially in said flange, said attaching flange including side edges, and wire receiving notches in said side edges for facilitating the attachment of a second wire to said terminal.

2. For use in electronic parts, a terminal and base construction, said terminal and base construction comprising a tubular base member having a longitudinal axis, a terminal, said terminal having at least one prong struck therefrom, said prong passing into said base member and securing said terminal to the arcuate surface of said base member parallel to said longitudinal axis, the formation of said prong presenting an opening in said terminal, said opening being spaced relative to said base member and forming in conjunction with an adjacent portion of said base surface a wire socket intermediate said terminal and said base member, said terminal including an attaching flange, said attaching flange being disposed in angular relation to the remainder of said terminal and extending away from said base member, said flange being connected to the remainder of said terminal intermediate the ends of said opening whereby said wire socket is disposed partially in said flange, said attaching flange including side edges, and wire receiving notches in said side edges for facilitating the attachment of a second wire to said terminal.

3. For use in electronic parts, a terminal and base construction, said terminal and base construction comprising a tubular base member having a longitudinal axis, a terminal, said terminal having at least one prong struck therefrom, said prong passing into said base member and securing said terminal to the arcuate surface of said base member parallel to said longitudinal axis, the formation of said prong presenting an opening in said terminal, said opening being spaced relative to said base member and forming in conjunction with an adjacent portion of said base surface a wire socket intermediate said terminal and said base member, said terminal including an attaching flange, said attaching flange being disposed in angular relation to the remainder of said terminal and extending away from said base member, said flange being connected to the remainder of said terminal intermediate the ends of said opening whereby said wire socket is disposed partially in said flange, said attaching flange including side edges, wire receiving notches in said side edges for facilitating the attachment of a second wire to said terminal, said wire receiving notches being tapered and facing away from said wire socket whereby a wire seated in

said wire receiving notches is urged away from said wire
socket.
